(57) **CLAIM**

The ornamental design for a kite packaging cap, as shown and described.

DESCRIPTION

FIG. 1 is a top perspective view of a kite packaging cap showing my new design;

FIG. 2 is a bottom perspective view of the design;

FIG. 3 is a front view of the design;

FIG. 4 is a rear view of the design;

FIG. 5 is a left side view of the design;

FIG. 6 is a right side view of the design;

FIG. 7 is a top view of the design; and,

FIG. 8 is a bottom view of the design.

The broken lines are shown for the purpose of illustrating the boundaries of the claim as well as environmental subject matter of an exemplary kite packaging container. None of the broken lines form part of the claim.

1 Claim, 7 Drawing Sheets**US D885,184 S**
